UNITED STATES PATENT OFFICE.

THOMAS S. HOMANS, OF HEMPSTEAD, NEW YORK, ASSIGNOR TO INTERNATIONAL
TYPESETTING MACHINE COMPANY, OF NEW YORK, N. Y., A CORPORATION OF
NEW YORK.

TYPOGRAPHICAL MACHINE.

1,153,080.

Specification of Letters Patent. Patented Sept. 7, 1915.

Application filed January 5, 1914. Serial No. 810,455.

To all whom it may concern:

Be it known that I, THOMAS S. HOMANS, a citizen of the United States, residing at Hempstead, in the county of Nassau and State of New York, have invented new and useful Improvements in Typographical Machines, of which the following is a specification.

My present invention relates to improvements in typographical machines and more especially to those of the linotype class adapted to receive interchangeably matrix containing magazines, and the primary object of the invention is to provide means whereby the operation of removing one magazine and applying another may be accomplished with facility and from the front of the machine.

To this end, the invention consists in certain improvements and combinations and arrangements of parts, all as will be herein-after more fully described, the novel features being pointed out particularly in the claims at the end of the specification.

25. In the accompanying drawings:—Figure 1 is an elevation of the right-hand side of a portion of a machine embodying the present invention; Fig. 2 is a front elevation of that portion of the machine shown in Fig. 1.

30. Similar parts are designated by the same reference characters in the several views.

The present invention is applicable generally to typographical machines adapted to receive interchangeable magazines, it being particularly adapted for use in connection with machines of the linotype class.

The preferred embodiment of the invention is shown in the present instance and will be hereinafter described in detail, but it will be understood that the invention is not restricted to the precise construction shown, as equivalent constructions within the scope of the claims may be used.

In the present instance 1 designates the upper portion of the main frame of the machine, it supporting the distributor bar 2 and matrix distributing screws 3 near the top thereof. At a lower level and at the front of the machine is arranged the assembler entrance 4.

5 designates a matrix containing magazine, this magazine being interchangeable with other magazines whereby different fonts of matrices can be brought into use.

55. The matrices are fed by gravity from the

channels in the magazine, the latter occupying an inclined position on the machine, the upper rear end of the magazine being located in proximity to the distributing mechanism and the lower forward end of the magazine being arranged to deliver matrices therefrom into the assembler entrance 4.

The machine is provided with a magazine frame 6 which is adapted to support each magazine in the position stated. In order to properly locate each magazine relatively to the frame 6, cross-bars 7 are provided on the under side of each magazine and are adapted to rest on the frame 6. A cross-bar 8 on the underside of the magazine and brackets 9 secured to the frame 6 serve to position the magazine both longitudinally and laterally, the bar 8 resting against the upper rear sides of the brackets 9 to limit the forward movement of the magazine, and projections 10 extending forwardly from the bar 8 coöperate with the inner sides of the brackets 9 and thereby position the magazine laterally. The brackets 9 have overhanging projections 11 which, when the magazine is in operative position, prevent lifting of the magazine from the frame 6, but owing to the tapered form of the magazine, the latter can be removed from the frame 6 after the magazine has been lifted to a point where the narrower portion of the magazine will pass between the overhanging projections on the brackets.

A distributor entrance 12 is provided which guides the matrices from the distributor bar 2 into the upper ends of the appropriate channels of the magazine, this entrance in the present instance being pivoted to the magazine frame 6 at 13 and a spring 14 serves to normally retain the entrance in proper position.

According to the present invention means is provided whereby the magazines can be applied and removed with facility from the front of the machine. In the construction shown, the lower forward end of the magazine frame 6 rests on a pair of brackets 15 which are secured to the main frame of the machine, and the rear portion of the magazine frame 6 is carried by arms 16, the latter in the construction shown being pivotally connected at their upper ends to the magazine frame 6 on the axis 17, and the lower ends of the arms 16 being pivoted to the main frame on the axis 18. Suitable stops 105

19 coöperate with the arms 16 and thereby limit the rearward movement of the arms 16 and the magazine frame 6. A pair of handles 20 are preferably attached to opposite sides of the magazine frame in order to facilitate lifting of the forward end of the frame 6 and the magazine thereon. The brackets 15 are also provided preferably with cam surfaces 21 over which the lower 10 end of the magazine frame 6 is adapted to ride while said frame and the magazine thereon are being shifted into a position in front of the machine. When the frame 6 and the magazine have been swung to the 15 limit of their forward and downward movement, as shown by the dotted lines in Fig. 1, the carrier arms 16 will rest on the brackets 15, and the magazine frame 6 and the magazine thereon will hang in a vertical position 20 in front of the machine and from the axis 17. When the frame 6 is in this position, the magazine thereon may be easily removed by lifting the same, thereby freeing it from the brackets 9, and after another magazine 25 has been applied to the frame 6 the latter may be swung into the full line position in Fig. 1, the forward and lower end of the frame 6 being returned to its position on the brackets 15. The cam-shaped guides 21 30 prevent striking of the magazine frame 6 upon the front of the assembler entrance 4 while such frame is being moved to or from operative position.

The present invention provides a simple 35 arrangement whereby the magazine supporting frame is carried from its normal position to a vertical position in front of the machine and then returned to normal position, this being easily accomplished in the construction shown by the operator standing at the front of the machine.

I claim as my invention:

1. In a machine of the class described, the combination with a main frame, of a 45 magazine supporting frame, a magazine movable longitudinally into engaged and disengaged relation therewith, and connections between the main frame and magazine supporting frame for guiding the latter 50 from operative position to a vertical position in front of the machine for application or removal of a magazine by lowering or lifting the same vertically.

2. In a machine of the class described, the combination with a main frame, of a 55 magazine frame, a magazine movable longitudinally into engaged and disengaged relation therewith and adapted to occupy an inclined operative position, and means for 60 guiding the magazine carrying frame to a vertical position in front of the machine to permit lifting of the magazine vertically therefrom.

3. In a machine of the class described, 65 the combination with a main frame, of a

magazine supporting frame, a magazine removable longitudinally from the upper end of said supporting frame, and means pivotally connecting the main frame and the upper rear portion of the magazine supporting frame and operative to guide the latter from an inclined operative position to a vertical position in front of the machine to permit removal of a magazine vertically from said supporting frame. 70

4. In a machine of the class described, the combination with a main frame, of a magazine supporting frame carrying a magazine removable longitudinally from the upper end thereof, and a pivotal connection between the main frame and the magazine supporting frame for holding the latter in an inclined operative position and for suspending the magazine supporting frame in vertical position in front of the 85 machine for application or removal of a magazine. 90

5. In a machine of the class described, the combination with a main frame, of a magazine supporting frame carrying a 90 magazine removable longitudinally from the upper end thereof, means pivotally connecting the main frame and the upper rear portion of the magazine supporting frame for carrying the upper rear portion of the latter into a position in front of the machine, and means for guiding the lower forward portion of the magazine supporting frame into such position. 95

6. In a machine of the class described, 100 the combination with a main frame, of a magazine supporting frame carrying a magazine removable longitudinally from the upper end thereof, means pivotally connecting the main frame and the upper rear 105 portion of the magazine supporting frame for carrying the upper rear portion of the latter into a position in front of the machine, and brackets arranged to coöperate with the forward lower ends of the magazine frame to hold the same in operative position. 110

7. In a machine of the class described, the combination with a main frame, of a magazine supporting frame carrying a 115 magazine removable longitudinally from the upper end thereof, means pivotally connecting the main frame and the upper rear portion of the magazine supporting frame for carrying the upper rear portion of the latter into a position in front of the machine, and brackets having guides to co-operate with the forward lower end of the magazine supporting frame as the latter is shifted to a position in front of the machine. 120

8. The combination with a main frame, of a magazine frame adapted to occupy an inclined operative position and carrying a magazine removable longitudinally from the 130

upper end thereof, brackets on the main frame coöperative with the forward lower end of the magazine supporting frame to hold the same in operative position and having guides to coöperate with the magazine supporting frame as the latter moves toward a vertical position in front of the machine, and arms pivotally connected to the main frame and the rear upper portion of the magazine supporting frame for supporting the latter in inclined operative position and for suspending the same in vertical position in front of the machine.

9. The combination with the main frame 15 of the machine, of a magazine supporting

frame, means for guiding the latter from an inclined operative position to a vertical position in front of the machine with the rear end of the magazine uppermost, and devices for retaining a magazine on said supporting frame and permitting removal of a magazine therefrom while in vertical position by relative upward movement of the magazine.

In testimony whereof I have hereunto set my hand in presence of two subscribing witnesses.

THOMAS S. HOMANS.
